TOP ROLL WEIGHTING DEVICES

Richard K. Butler, Whitman, Mass., assignor to Machine-craft, Inc., Whitman, Mass., a corporation of Massachusetts

Filed May 31, 1960, Ser. No. 32,740
18 Claims. (Cl. 19—267)

This invention relates to spinning and roving frames, and forms a part of a comprehensive modernization of existing frames to improve and increase their production and make them easier to run. It has to do with the means of applying pressure to the top rolls of the pairs of opposed rolls which successively engage the several strands of textile fibers and travel at progressively increased speed, to attenuate or "draw down" the strands and bring the fibers thereof into parallel relation. The rolls of each pair must be pressed strongly together in order to make them turn in unison and to enable them to grip the fibers, and for these purposes the top drawing rolls have been loosely mounted by their ends in cap bars and pressed down against the bottom rolls by devices termed saddles bearing against the necks between the two bosses of each top roll, the saddles being conventionally pulled downward by suitable links and levers with weights hanging from the ends of the lever.

These hanging weights have well known drawbacks, one of which is their tendency to swing and jump under the vibration of the spinning frame or the underlying mill floor, with resulting fluctuations of roll pressure which vary the grip of the rolls on the fibers, causing the fibers to be fed by the rolls at unequal speeds and quantities, thus making the yarn uneven in density and strength and hence of lessened value. Also, wide differences in the pressures applied to different strands in the same machine result from inaccuracies in the linkage system. Another drawback has been the amount of muscular effort involved in lifting the weights to unweight the top rolls as required for replacement or for their removal at frequent intervals for various purposes, most commonly to clear them of fibers wrapped around them or adhering to them, and also to avoid the formation of flat places by continued pressure on the cots while the machine is at rest.

To avoid these and other difficulties, many forms of springs have been proposed to weight the top rolls, thus obviating the erratic action of the hanging weights due to their inertia. When provided with suitable leverage for multiplying their power, these springs make it possible to increase greatly the weighting of the rolls as required in the long-draft spinning of synthetic fibers, where a weighting of 200 lbs. or more is often used, divided between the front, middle and back top rolls serving the two strands being drafted by the respective bosses of these three rolls. However, the space between the drawing rolls and the roller beam on which they are mounted in the conventional type of spinning frame affords scant room for these springs, their perches, and the necessary levers or other devices for compressing or unloading the springs so as to permit the weighting and unweighting of the rolls, and hence it has been the practice to mount the springs as well as certain of their appurtenances beneath the roller beam, running the links or stirrups or other tractive elements through holes in the roller beam so as to reach up and connect with the saddles which bear down on the roll necks. While this does get the springs under the shelter of the roller beam so that they collect little or no lint to fall off in bunches and get caught and twisted into the yarns to lower their quality, it leaves the roller beam obstructed by the stirrups and spring-compressing or unweighting levers or devices. Not only does this arrangement make it more difficult and

2

time-consuming to keep the roller beam cleared of the ever-present lint and fly, but it makes it extremely difficult to equalize the pressure on all the top rolls and to change the total weighting of the top rolls as required when the size of yarn and character of fiber to be spun are to be changed.

Another alternative form of spring weighting in common use employs a "top arm," so-called, a channel member of inverted U-shape overlying the necks of the front, middle and back top rolls, each roll being held by its neck in an end of a short arm pivoted by its rear end within the channel and with a spring compressed between the web of the channel member and the roll-holding end of the arm to press the arm and thus the top roll downward, these devices usually also positioning the top roll without the use of cap bars. Thus each top roll has its own spring to weight it, the channel member being removably clamped down over the three lines of rolls. While this form greatly simplifies the unweighting and reweighting of the top rolls, and leaves the roller beam uncluttered and accessible, it is impossible to change the total weighting or the relative weighting of a set of front, middle, and back rolls except through the substitution of different springs throughout the entire frame, which takes two men about three days to do, there being three or more springs to be changed for each pair of the 240 or more spindles in the frame.

It is the main object of this invention to avoid these shortcomings of the prior structures, so as to provide an improved spring-weighting device for the top rolls which can be cheaply and easily manufactured almost wholly out of commercially available forms of steel stock, which will permit changing the roll weighting through a wide range, which will leave the roller beam unobstructed and will itself afford a minimum of lint collecting surfaces, and which will make it quick and easy to unweight the top rolls and disconnect the linkage from the saddle or other pressure device as well as to reweight the rolls, by means accessible from in front of the frame 40 and above the roller beam.

A further object is to provide apt means for weighting the top rolls when the pairs of drawing rolls and the strands passing through them are disposed in a plane at a high angle to the roller beam's top surface. The 45 force used to press the rolls together needs to be exerted substantially at right angles to such plane for efficiency. Hence spring or dead weighting from below the roller beam is practically precluded, and dead weighting above the roller beam is impossible, for lack of space. A new way of arranging the spring weighting above the 50 beam is required which will be convenient and accessible for applying, releasing, and changing the weighting, without encroaching on the creel area and interfering with the supply of roving bobbins therein which feed the drawing rolls.

Other objects of the invention and the manner of their attainment are as set forth hereinafter.

An illustrative embodiment of the invention is shown in the accompanying drawings, in which:

60 FIG. 1 is a vertical transverse section through the roller beam, top and bottom drawing rolls and back bar of a spinning frame adjacent one of the roll stands, showing the top rolls and their guiding and positioning means, and with the weighting devices applied.

65 FIG. 2 is an axial section of the weighting device together with the hand lever which applies and relieves the weighting pressure to a top roll, and the rail whereby it is mounted.

70 FIG. 3 is a view on line 3—3 of FIG. 1, below the roll slide.

75 FIG. 4 is a view in section on line 4—4 of FIG. 2. The invention is shown applied to the improved apron

drafting spinning frame of Cotchett Patent No. 2,865,057, granted Dec. 23, 1958. Herein a roll stand 1 supports the bottom drawing rolls 3, 5, 7, with the drafting plane, defined by the paths of the strands 9 being drawn and the nips of these rolls which draw them, at a steep angle of around 60° from the horizontal surface of roller beam 11. The top rolls 13, 15, 17 are of the type devoid of pintles or gudgeons on their ends. The means of holding the top rolls in working relation with their respective bottom rolls is of the so-called capbarless type in which overlapping members 19, 21 of inverted U-section hold the top rolls by their necks alone and serve to position and guide the top rolls and also act as saddle means to apply to them the weighting pressure created by the devices of the present invention. These members 19, 21 are slotted at their rear ends and both are hooked over a stub shaft 23 mounted on the regular back bar 25 which guides the strand 9 of roving being taken from a supply bobbin in the creel (not shown), preferably that of my companion patent application Serial No. 783,902, filed Dec. 30, 1958, devised to take full advantage of the additional space provided for the supply bobbins by the steeply tilted drafting plane.

The bottom roll bearings 27, 29, 31 are mounted on roll stand 1 with capacity for adjustment toward and from each other to vary the roll setting as needed, by means of cap screws 33 put through longitudinal slots in the roll slide 340 of the stand 1. The top roll guiding members 19, 21, are made extensible for the same purpose.

In accordance with the present invention, each top roll guiding member 19 is connected by its hook 35 and a sheet metal stirrup 37, having an elongated hole or slot at each end, with another hook 39 formed on a weighting or loading lever 41 pivoted at 42 between two integral spaced lugs 44 extending from the side of a casting 43 of tubular cylindrical form equipped with oppositely extending mounting lugs 40 at its upper end, whereby it is mounted by screws 48 in register with a suitable aperture 34 in one web of an angle iron rail 49 mounted adjacent the bottom roll bearings in a manner to be described at the under side of bearing slide 340 of stand 1. Within the bore of casting 43 is fixed, as by press-fitting, a cylindrical sleeve or capsule 45 of seamless steel tubing extending through the hole 34 in rail 49 and forming the guide, container and lint-shield for an expanding coil spring 46.

The capsule 45 is internally threaded at its free end to receive a cylindrical threaded plug 50 against which the coil spring 46 rests as its perch. Within the other end of the spring is fitted a flanged header plug or plunger 51 sliding freely inside capsule 45 and against which the spring exerts its force and which thus transmits the spring pressure to an arm 47 forming an integral part of the loading lever 41 and so disposed with respect to hook 39 and pivot 42 as to form a bell-crank transmitting the force of spring 46 as a tractive force to stirrup 37.

Thus the force of spring 46 exerted on arm 47 strives to rotate the loading lever counterclockwise about pivot 42, and in so doing urges stirrup 37 in a direction at right angles to the guiding, positioning and weighting members 19 and 21.

The pull of stirrup 37 is delivered through hook 35 to the top member 19, within the channel of which the hook 35 is mounted by cap screws 53 and washers with capacity for adjustment at right angles to the roll axes along a longitudinal slot formed for the screw in member 19.

A part of the load thus applied to top member 19 is used to weight the front top roll 13, being delivered directly to the neck of front top roll 13 by means of the gooseneck extension 55 of member 19. This gooseneck bears directly on the sleeve or spacer 57 on the neck of the ball-bearing front top roll 13 and presses it against bottom roll 3. The remainder of the load is applied to member 21 and distributed between middle top roll 15

and back top roll 17. It is transmitted by a roller 59 engaging with the under side of member 19 within the channel thereof and positioned by a mount 58 fixed on the member 21 with capacity for adjustment lengthwise of member 21. By this adjustment the weighting thus applied to the middle and back top rolls is divided between them as desired.

All the springs 46 in use at a given time on the spinning frame are carefully calibrated in advance to have a known and equal strength when compressed to the same overall length. The screw plugs 50 are the means for compressing the springs all to the same length, and hence for obtaining uniform weighting of the rolls throughout the spinning frame, assuming of course that the devices are properly mounted and that uniform distribution is made of the weighting delivered to the front, middle and back top rolls by each spring and stirrup by the means just described.

The rail 49 of angle iron on which the several spring weighting devices are mounted is made in lengths each one roll section long, that is, each length extends from one roll stand to the next stand. In each length of rail 49 are fixed the necessary number of spring-weighting units to serve each pair of roll holders 19, 21, commonly three pairs, included between adjacent roll stands. Each length is mounted by bolts 61 upon a short length 63 of similar angle iron fixed by one flange to the under side of roll slide 340 by the same bolt 33 which fixes the middle bottom roll bearing 29 in position on the slide 340. The rail 49 being thus suspended from the middle bottom roll bearings, whenever these roll bearings are shifted to vary the roll setting (spacing), by loosening the bolts 33 and sliding these parts along the slides 340, the rail 49 and the spring-weighting devices retain their initial position with respect to the middle rolls and are automatically shifted along the roll slides with these bearings.

Hence the spring-weighting devices are maintained always in the same spaced and angular relation to the middle drawing rolls with their roll-weighting force unchanged regardless of changes in roll settings, since any adjustment of bearings 29 along the stands 1 carries with it the junction pieces 63 and the lengths of rail 49 with their spring capsules 43, 45.

Both the holes 34 in rail 49 in which the spring-weighting devices are mounted, and the holes therein for screws 48, are made oversized to allow adjustment of each spring-weighting device up or down and laterally.

In installing the novel weighting system, and to attain uniformity of the effective roll-weighting force of the several devices throughout the spinning frame, a gage in the form of a simple narrow strip of metal of uniform thickness is inserted and gripped between an arm or stop 67 on lever 41 and the confronting surface 68 of the casting 43 of each successive device to be installed. With the several weighting devices loosely mounted in their holes 34 and with their lugs 40 against the rail 49, and with the gage still in place, the stirrup 37 of each device in turn is engaged with hooks 35 and 39 and the weighting device slid downward and rearward transversely of rail 49 as far as the stirrup permits. Thereupon screws 48 are tightened to fix the device in its working position. The gage is then withdrawn.

In this manner all the weighting devices are made to exert the same loading force on the top rolls, since the forces resulting from the combined spring tension and leverage are equal from unit to unit throughout the frame, when the hand levers 41 are each at the same angle to the axis of the capsule and spring, which is the result of this method of installation.

A novel advantage flows from this arrangement. The hand levers serve as indicators of the uniformity of loading throughout the frame. Any hand lever 41 that is out of line with the rest of the hand levers in the rank extending throughout the length of the frame is necessarily exerting greater or lesser weighting on its stirrup because

its leverage is different. Thus a quick glance down the line of hand levers with the eye at their level enables the operator to spot any departure from the intended roll weighting. The remedy is the same operation followed in installing the devices: inserting the spacer gage between stop 67 and wall 68, loosening screws 48, taking up the slack in the stirrup connections, re-tightening screws 48, and removal of the gage.

To unweight the top rolls for removal and replacement, or when the machine is idle, the hand lever 41 is momentarily pulled forward and upward manually by means of its finger piece 65. This causes arm 47 to act as a cam forcing the plunger 51 inward and relieves the pull of the hook 39 on the stirrup 37, which falls off from the hook as soon as the latter clears the bottom of the slot in the stirrup. As the attendant releases the lever 41 stop 67 thereon engages the wall 68 of casting 43 and keeps the lever from swinging back out of convenient reach. Stirrup 37 is then easily unhooked from hook 35, and the guiding, positioning and weighting members 19, 21 are free to be lifted off successively, carrying with them the top rolls, after freeing the aprons.

Re-weighting is accomplished in obvious manner, stirrup 37 being re-engaged with hook 35 on member 19 and with hook 39 on the hand lever after the latter has been raised to bring hook 37 above the end of its slot in the stirrup. Release of the hand lever reinstates the load of spring 46 on the stirrup and parts connected therewith.

The unweighting and re-weighting are one-hand operations, requiring only a moment's time and very little physical effort, on account of the favorable leverage afforded by the handle. By lifting the lever with the palm of his hand, the attendant can easily guide the stirrup slot over the hook 39 with the fingers of the same hand. The bottom end of the stirrup is preferably forked below the slot which receives the hook 39, so that the forked end can be placed astride the shank of the lever 41 and thus serve to effect rapid alignment of the stirrup's slot with hook 39 as the stirrup is slid along the handle toward the hook.

As noted, when it is desired to change the weighting applied by the respective weighting devices, i.e., the total weighting applied to all three top rolls weighted by a single spring, the coil springs 46 are simply put under more compression to get heavier weighting, or their tension is relieved to get lesser weighting, by screwing the plug 50 in or out with a screw-driver. The extent of protrusion or intrusion of the respective plugs 50 gives visual indication of the relative tension of the several springs.

Where changes in roll pressure beyond the range of one set of springs 46 are needed, other springs of the required tension are substituted throughout the frame for those initially used in the capsules 45.

The improved structure is of course applicable to spinning frames of types employing cap bars and saddles for guiding and weighting the top rolls, the stirrup 37 or its equivalent being attached to the forepart of the saddle in usual or any preferred manner.

The device of the present invention attains the known advantages of spring-weighting over dead-weighting in a form in which uniform weighting of all the corresponding rolls is attained and demonstrated, and weighting and un-weighting is quick and easy; in which the amount of weighting can be accurately predetermined and is capable of adjustment as desired within an ample range, with further capacity for change to a higher or lower range. It attains these advantages while additionally leaving the roller beam clear and unobstructed, and while itself providing a minimum of surfaces on which lint can collect and those easily cleaned. Further, and most important from the standpoint of its usefulness, the application and release of the roll-loading pressure is effected entirely from the spinner's usual position while standing erect in front of the frame, by touch alone, sight unseen. The struc-

ture is cheaply and easily made from stock of standard commercially available forms, with a minimum of machining and no critical dimensions, and is adapted for installation in new frames and also in various existing frames, for converting and modernizing them in the interest of greater economy.

A still further advantage is that since all the springs react wholly against parts mounted on the roll stands and not on the roller beam, the forces created by the weighting means are confined to the parts of and on the roll stands, with no forces acting between the roll bearings and the roller beam to require strong and hence heavy roll stands to sustain them. Thus light-weight roll stands 1 made from standard commercial steel stock by simple bending and punching operations are adequate where previously much costlier cast-iron roll stands have been required. This economy of weight and cost is of course additional to that attained through obviating the rugged construction of both spinning frames and mill buildings which gravity type dead-weighting of the top rolls required.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but what I do claim is:

- 30 1. A spinning frame having in combination top and bottom drawing rolls, a roller beam, roll stands, means overlying and engaging the necks of the top rolls, a rail mounted on the roll stands extending parallel to the rolls, coil springs in fixed locations on the rail in spaced relation to the roll stands and with their axes parallel to the common plane defined by the nips of the rolls, and means transmitting tension from the springs to the means engaging the roll necks.
- 35 2. A spinning frame having in combination front, middle and back top rolls, front, middle and back bottom rolls, roll stands, bearings for the bottom rolls on the roll stands, of which the middle bottom roll bearings are shiftable along the roll stands to vary the roll spacing a rail suspended from the middle bottom roll bearings, and spring roll weighting means mounted on the rail and weighting the top rolls.
- 40 3. A spinning frame having in combination top and bottom drawing rolls, bearings for the bottom rolls, a roller beam, roll stands on the roller beam each having a portion forming a roll-bearing slide, a rail spanning the space between one roll stand and the next roll stand and adjustable along the bearing slide transversely of the roller beam, a plurality of coil springs mounted on the rail in spaced relation to the roll stands, means overlying and engaging the necks of the top rolls, and means transmitting tension from the springs to the means engaging the roll necks.
- 45 4. Mechanism for drawing textile fibers arranged in strand form, having in combination a roller beam, top and bottom drawing rolls feeding and drafting the strands, roll stands, a rail extending from one stand to the next above the roller beam, coil springs mounted on the rail with their axes parallel to the paths of the strands through the rolls, and means transmitting tension from the springs to the top rolls.
- 50 5. A spinning frame having in combination top and bottom drawing rolls, a roller beam, roll guiding and positioning means holding the top rolls in cooperating relation to the bottom rolls by their necks alone, roll stands, bearings for the bottom rolls mounted on the roll stands with capacity for adjustment of their relative spaced relation, and coil springs weighting the roll guiding and positioning means and mounted on the roll stands with capacity for shift with the bearings along the roll stands.
- 55 6. The combination according to claim 5 in which the

coil springs are automatically shifted in unison with certain of the bottom roll bearings during the adjustment of the latter's relative spaced relation.

7. A spinning frame having in combination top and bottom drawing rolls, a roller beam, roll-guiding and positioning means holding the top rolls in cooperating relation to the bottom rolls by their necks alone, roll stands, bearings for the bottom rolls mounted on the roll stands with capacity for adjustment of their relative spaced relation, a rail suspended from certain bottom roll bearings, springs mounted on the rail and adapted to exert a force in a direction parallel to the direction of movement of the bearings in adjusting their spaced relation, and means transmitting the said force to the roll-guiding and positioning means in a direction at right angles to its initial direction, whereby to weight the top rolls.

8. A spinning frame having in combination a roller beam, roll stands thereon, top and bottom drawing rolls disposed with their nips all in a common plane, a member mounted on the roll stands below the rolls and extending parallel to the bottom rolls, spring guides fixed on the member and extending angularly therefrom and parallel to the said plane, expanding coil springs within the guides, weight-applying means engaging the top rolls, and means transmitting the force of the springs to the weight-applying means at right angles to such plane.

9. A spinning frame having in combination top and bottom drawing rolls having their nips disposed in a common plane, a roller beam, roll stands, weight-applying means engaging a top roll, a member below and parallel to the rolls and fixed by both its ends to the roll stands and having a transverse hole, a tube fixed in the hole in the member with its axis parallel to the common plane, an expanding coil spring within the tube, and a plunger also within the tube and adapted to actuate the weight-applying means and biased by the axis of the spring.

10. A spinning frame having in combination top and bottom drawing rolls, roll stands, weight-applying means engaging the top rolls, a member having its ends fixed to the roll stands, a tubular spring guide fixed in a hole in the member, an expanding coil spring retained within the guide, a stirrup attached to the weight-applying means, a plunger in the guide receiving the thrust of the spring, a pivot laterally offset from the spring, and a bell-crank pivoted thereon engaged by the plunger and transmitting the thrust applied thereto by the spring as a tractive force to the stirrup.

11. Spring weighting means for the top rolls of a spinning frame, having in combination roll stands, weight-applying means engaging the top rolls, a plunger in connection with the weight-applying means, an expanding coil spring biasing the plunger and through it the weight-applying means, a sleeve about the spring and in fixed connection with the roll stands, and lever means fulcrumed on the sleeve and adapted to compress the spring and relieve the bias of the weight-applying means.

12. A spinning frame having in combination top and bottom drawing rolls, a roller beam, roll stands on the latter, means overlying and engaging the necks of a plurality of the top rolls, a plurality of equally stressed coil springs, means mounting the coil springs in adjustable positions on the roll stands, and means transmitting ten-

sion from the springs to the respective means overlying and engaging the roll necks, including levers transmitting equal tension when at equal angles to the axes of their respective coil springs, such angles being established by adjustment of the positions of the springs on the stands.

13. A spinning frame having in combination top and bottom drawing rolls, a roller beam, roll stands on such beam, roll-weighting means adapted to load the top rolls, a plurality of coil springs having equal strength when compressed to the same length, means mounting the coil springs in adjustable positions and in parallel relation to each other on the roll stands, and means transmitting the force of the springs to the roll-weighting means including levers compressing the respective springs to equal lengths when at the same angle to the axes of their respective springs, and visually demonstrating unequal spring compression and resulting unequal roll-weighting by a different angular position to the axes of their respective springs.

14. A spinning frame having in combination top and bottom drawing rolls, a roller beam, roll stands, bearings for the bottom rolls on the stands, a spring supported by the bearings, weighting means engaging the top roll necks, means transmitting the spring's force to the weighting means, and means for varying the point of application of the spring's force to the weighting means.

15. The combination according to claim 14 having means for varying the total force applied by the spring to the weighting means.

16. A spinning frame having in combination opposed top and bottom drawing rolls, a roller beam, roll stands, means overlying and engaging the necks of a plurality of the top rolls, a coil spring, means mounting the coil spring on the roll stands below the rolls with the spring's axis below and parallel to the common plane defined by the nips of the rolls, and tractive means connecting the spring and the means overlying and engaging the roll necks.

17. The combination according to claim 16 including means providing for shift of the point of connection of the tractive means with the means overlying the roll necks in a direction at right angles to the roll axes.

18. A spinning frame having in combination opposed top and bottom drawing rolls, a roller beam, roll stands, means overlying and engaging the necks of a plurality of the top rolls, a coil spring, means mounting the coil spring on the roll stands with its axis below and parallel to the common plane defined by the nips of the rolls, tractive means connected to the means overlying and engaging the roll necks and disposed at an angle to the spring's axis, and a bell-crank transmitting tension from the spring to the tractive means.
